UNITED STATES PATENT OFFICE.

CHARLES H. BRIGDEN, OF YONKERS, NEW YORK.

LOCK.

SPECIFICATION forming part of Letters Patent No. 699,831, dated May 13, 1902.

Application filed June 17, 1899. Serial No. 720,833. (No model.)

To all whom it may concern:

Be it known that I, CHARLES H. BRIGDEN, of Yonkers, in the county of Westchester and State of New York, have invented certain new and useful Improvements in Locks, of which the following is a specification.

This invention relates to locks; and it consists in certain novel features of construction and arrangement therein hereinafter described and claimed.

The invention, as subsequently described herein, is embodied in a hasp-lock, such as those employed on trunks or for other purposes; and one object of the invention is to provide an improved construction of that type of lock in which the screws or other attaching devices by means of which the lock is secured to its base may be covered over and protected.

The invention also has for its object to improve in general the construction of locks, as hereinafter explained.

Of the accompanying drawings, Figure 1 represents a front elevation of a lock constructed in accordance with my invention, showing also the parts which it secures or locks. Fig. 2 represents a similar view with the hasp thrown back. Figs. 3 and 4 represent views in elevation, showing the parts inside the casing in different positions. Fig. 5 represents a similar view with the tumblers removed. Fig. 6 represents a section on the line 6 6 of Fig. 1. Figs. 7 and 8 represent sections on the lines 7 8 7 8 of Fig. 1, showing the key inserted and the parts in different positions. Fig. 8^a represents a detail view, hereinafter referred to.

The same reference characters represent the same parts in all the figures.

Referring to the drawings, *a* and *b* represent the parts to be secured by the lock, the said parts being, for instance, a door and jamb or two doors or the body and lid of a trunk. The form of lock represented in Figs. 1 to 8^a, inclusive, is particularly adapted for use in situations where a hasp and padlock are ordinarily employed.

c designates a plate having holes for the reception of screws *c' c'*, bolts, or other attaching devices, whereby the said plate is attached to the door or other member *a*. In alignment with the plate *c* on the jamb or

other member *b* is mounted a second plate *d*, provided with a keeper *d'*, formed as a staple and having holes for the reception of screws *d' d'* or equivalent attaching devices for securing the said plate to the member *b*.

e is a plate or hasp hinged at *e'* to the end of the plate *c* farthest from the edge of the door or member *a* and having an aperture *e²* near the end opposite the hinge, which is adapted to be entered by the staple *d'* when the plate *e* is thrown over to cover the plates *c* and *d*, as represented in Figs. 1 and 6. A bolt *f*, forming part of a lock mechanism hereinafter described and located behind the aperture *e²*, is adapted to enter the eye of the staple *d'* when the plate *e* is positioned as described, so as to lock said plate to the staple. The plate *e* and its bolt mechanism therefor operate somewhat after the manner of the ordinary hasp and padlock, and when the bolt is withdrawn the hasp *e* can be thrown back, as represented in Fig. 2, to unlock the members *a* and *b*.

It will be noted that when the plate *e* is in locking engagement with the staple *d'*, as represented in Figs. 1 and 6, the plates *c* and *d* are covered over, and it is then impossible to obtain access to the heads of the screws *c' d'* except by withdrawing the bolt *f* or breaking the lock.

g is a cap attached by screws *g' g'* to the plate *e* and constituting, together with said plate, a casing which incloses the mechanism of the lock. The screws *g'* are screwed into tapped lugs *g² g¹²*, formed on the inside of the cap *g* and flush with its inner edge. The bolt *f*, which is beveled on its end, so as to snap into engagement with the staple *d'*, is mounted between guiding-lugs *g³ g³* inside of the cap *g* and is yieldingly projected into locking position by means of a bar-spring *h*, interposed between said bolt and an annular boss *g⁴*, formed on the interior of the cap *g*.

i is a bolt-retracting plate mounted to slide in the same longitudinal direction as the bolt *f* and having formed near one end a slot *i'*, elongated in the direction of the movement of the bolt, which slot is occupied by a pin *f'*, secured to the rear end of the bolt *f*. The bolt is thereby permitted to snap into engagement with its staple without moving the plate *i*. As shown in Fig. 6, the bolt is slotted lon-

itudinally at f^2 to allow for its movement with respect to the plate.

j is a knob located on the outer side of the cap g and attached by a screw j' to the plate i , the stem of said knob passing through an elongated slot g^5 , formed in the wall of the cap. By manipulating the knob the plate i when unobstructed can be moved longitudinally to retract the bolt f , the two being again projected by the spring h when said knob is released. At its rear end the plate i is recessed at i^2 to provide a guiding engagement with the tapped stud g^{12} during the longitudinal movement of the plate. Said plate i also has a slot i^3 formed in it near its rear end to permit the passage of the key for operating the bolt. Said key k is represented in Figs. 7 and 8.

Located inside the casing and mounted to oscillate within the annular boss g^4 is a circular disk m , formed with an elongated slot m' for the passage of the flat stem of the key k . The cap g is formed with a keyhole g^6 in register with the center of the disk m , through which the key is adapted to be inserted, and the disk m partially covers said keyhole, so as to protect the lock mechanism from tampering. The disk also partly supports the key when it is turned in the lock. A hole e^8 is formed in the plate e for retaining and guiding the end of the key.

n is a second disk mounted next the disk m , within the annular boss g^4 , and illustrated in detail in Fig. 8^a. It has a central aperture n' for the passage of the stem of the key k and two lugs n^3 n^2 , projecting from opposite sides of said aperture and adapted to be engaged by the wards k' k' of the key, whereby when the key is turned said disk n is partially rotated. Two lugs n^3 n^3 , located at separate points on the margin of the disk n , are arranged to engage abutments i^4 i^4 on the plate i , whereby when the disk n is rotated by the key said plate i and the bolt f will be retracted.

o o' represent flat bolt-controlling tumblers pivoted to the tapped stud g^{12} and having legs or forks 2 2 , between which the key k is adapted to be inserted. o o' are bar-springs attached at one end to the respective tumblers o and engaged at their other ends with opposite sides of the cap g . Said springs normally operate to hold the ends of the legs 2 2 on the tumblers in the path of two separated stops or lips i^5 i^5 , turned up on the intermediate portion of the plate i , whereby the retraction of said plate is normally prevented. This position of the parts is shown in Figs. 3 and 7. The key k has wards k^2 k^2 , which when said key is inserted in the keyhole g^6 and turned lengthwise thereof, as represented in Fig. 7, pass through the holes of the disks and plate and between the legs of the tumblers without disturbing the position of said tumblers; but when the key is turned crosswise, as represented in Fig. 8, the said wards engage the

inner sides of the legs 2 2 of the respective tumblers and move said tumblers into register, bringing their legs 2 in alinement with the space between the stops i^5 i^5 and out of the path of said stops, as represented in Fig. 4. The continued rotation of the key then retracts the plate i and bolt f , as previously described.

I further provide a tumbler-displacing device for releasing the bolt and permitting it to be operated by hand by manipulating the knob j . Said device, as here shown, consists of a small rotary disk p , mounted in a shallow counterbore on the inner side of the plate e and exposed through a hole e^4 in said plate. The head of said disk is provided with a slot p' , adapted to receive the end of the key k , so as to turn the disk, and on its inner side is formed with a cross-bar p^2 , interposed between the legs 2 2 on the tumblers o and adapted when turned longitudinally of said legs, as represented in Fig. 3, to allow the tumblers to obstruct the plate i and prevent the retraction of the bolt. When the disk is rotated to turn the bar p^2 crosswise the said legs, however, the ends of the bar form abutments, acting against the inner edges of the legs, whereby the tumblers are brought into register, as shown in Fig. 4, in the same manner as when operated by the key. The plate i may then be retracted by manipulating the knob j .

It will be seen that the disk p , being on the inner side of the lock-casing, is inaccessible except when the hasp or lock-casing is thrown back, as shown in Fig. 2.

I do not confine myself to the exact details herein set forth, as the same may be variously modified without departing from the spirit of my invention.

I claim—

1. A lock comprising a plate having holes adapted to receive screws or other attaching devices, a hasp hinged thereto and arranged to close over said plate and carrying a spring-projected bolt, key-operated means for retracting said bolt, tumbler mechanism for normally preventing the retraction of the bolt except by a key, and means accessible solely when the hasp is opened for displacing the tumbler mechanism to permit the bolt to be retracted without the use of a key.

2. A lock comprising a latching-bolt, a bolt-retracting plate, a slot in one of said members elongated longitudinally of the bolt, and a pin on the other member occupying said slot, a spring engaged primarily with the bolt and normally projecting said bolt and the plate, a key-operated member adapted to engage and retract the plate, and thereby retract the bolt, a knob projecting from the bolt-retracting plate, and one or more key-operated tumblers normally obstructing the plate and preventing its retraction.

3. A lock comprising a casing, a bolt mounted therein, key-actuated means for operating said bolt, a series of bolt-controlling tum-

blers normally spring-held in bolt-obstructing positions and movable in opposite directions into bolt-releasing positions, a casing inclosing said parts, and a rotary member 5 mounted in the casing and exposed externally through a hole therein, said member having tumbler-displacing abutments interposed between the tumblers and adapted when the member is rotated, to move the tumblers into 10 bolt-releasing positions.

4. A lock comprising a plate, a hasp hinged thereto and provided with a lock-casing, a

bolt mounted in said casing, a series of key-operated bolt-controlling tumblers within the casing, a bolt-retracting knob located on the 15 outer side of the casing and a tumbler-displacing device located on the inner side of the casing.

In testimony whereof I have affixed my signature in presence of two witnesses.

CHARLES H. BRIGDEN.
